MULTIPLE DRINK MIXING MACHINE

Le Roy A. Brown and John E. Brotheridge, Rock Falls, Ill., assignors to Prince Castle Mfg. Division, Inc., Sterling, Ill., a corporation of Illinois

Application February 23, 1954, Serial No. 411,701

6 Claims. (Cl. 259—131)

The present invention relates to multiple drink mixing machines of the general type disclosed in Patents 2,531,989, Prince et al. and 2,619,332, Prince et al., both assigned to the same assignee as the present application.

Multiple drink mixing machines have been extensively sold on the market in the form of a unitary structure occupying a relatively small amount of space in which a plurality of separate mixing mechanisms can be operated simultaneously or individually with a single motor acting as the source of power for all of the separate mixing mechanisms. In the above mentioned patents there is disclosed a multiple drink mixing machine which comprises a base having an upstanding column from the upper portion of which depend a plurality of spaced apart rotatable drink mixing spindles. Also associated with the column are means adapted to receive a plurality of cups into each of which a rotatable mixing spindle is adapted to depend and when rotated to mix the drink in the cup. The base of the machine is formed as a stationary tray to catch the dripping from any of the spindles thereby insuring cleanliness. Also in such apparatus there is supported a suitable motor of sufficiently large size so that there is never any question about it slowing down or not being able to give the same efficient mixing under heavy loads. This motor drives a friction wheel and suitable means are associated with each mixing spindle to selectively cause the spindle to move into driving engagement with this friction wheel.

In such prior art mixers it has been the practice to employ a supporting spider in the form of a casting which casting or spider was supported from the upright column associated with the base of the mixer. To support a motor with its shaft in a vertical direction from such spider, it was necessary to drill and tap the end bell of the motor at the upper end thereof. This meant that in general the motors of one manufacturer had to be used since motors of different manufacturers are of generally different construction and the suitable cast spider operative with one manufacturer's motor might be completely unsatisfactory for another. It would be desirable to provide an arrangement in which any style motor which will fit into the space provided for the motor in the unit can be employed and can readily be supported without the requirement of drilling and tapping holes and without the limitation of a particular spider for a particular motor.

In the multiple drink mixing machines heretofore extensively sold on the market there was provided a manual switch which was turned on by the operator whenever the mixer was to be used whether one or any number of spindles were to be put into operation, and when it was desired to stop the motor the switch had to be turned off. It would be desirable to provide an automatic arrangement whereby whenever a container with material to be mixed was associated with any particular mixing spindle that the motor would be turned on and, when all such containers were removed and no further mixing was required, the motor would automatically be shut off. With such an arrangement the operator would not have

2

to actuate a switch, which might be difficult at times particularly when he might well have a cup or container in each hand containing material to be mixed. Under such a situation with no automatic means for starting the mixer, it would be necessary for the operator to set down one container and turn on the motor after which he could continue the operation.

Accordingly, it is an object of the present invention to provide a new and improved multiple drink mixing machine.

It is another object of the present invention to provide a multiple drink mixing machine with motor supporting means capable of accommodating any type of motor without the requirement of especially adapting the motor for proper support therein.

Still another object of the present invention resides in the provision of an improved automatic switch in which a single switch is actuated whenever any one of the mixing spindles has a container associated therewith in mixing position.

It is a further object of the present invention to provide an improved multiple spindle mixing device in which a stamped sheet metal supporting spider is employed capable of supporting any conventional electric motor which can be accommodated within the chamber provided for such motor.

Further objects and advantages of the present invention will become apparent as the following description proceeds and the features of novelty which characterize the invention will be pointed out with particularity in the claims annexed to and forming a part of this specification.

For a better understanding of the present invention, reference may be had to the accompanying drawings in which:

Fig. 1 is a small perspective view of a multiple spindle drink mixing machine embodying the present invention;

Fig. 2 is a greatly enlarged top view of the device of Fig. 1 with the top cover removed and certain portions shown in section better to illustrate the present invention;

Fig. 3 is a sectional view of the upper part of the drink mixing machine of Fig. 1 with certain parts cut away better to illustrate the present invention and with the motor switch in the open position;

Fig. 4 is a view similar to Fig. 3 with the top cover removed and with a container for mixing a drink in position whereby the control mechanism is in a different position from that shown in Fig. 3 and the motor switch in the closed position;

Fig. 5 is an enlarged front view of the cup-rest of Figs. 1 and 4 of the drawings;

Fig. 6 is an enlarged sectional view taken on line 6—6 of Fig. 3, assuming that Fig. 3 shows the complete structure; and

Fig. 7 is a perspective view of the switch control structure employed in the multiple spindle mixer of the present invention.

Referring now to the drawings, there is illustrated in Fig. 1 a complete drink mixing machine embodying the features of the present invention, which machine is designated generally by the reference numeral 10. As shown this multiple drink mixing machine comprises a flat stationary base indicated generally at 11 which is provided with a depressed somewhat semicircular portion and a surrounding upstanding rim so as to provide a shallow drip tray 12. This base member 11 is preferably a stamping of stainless steel, although it might comprise a stamping or casting of any suitable metal. The stainless steel is preferable by virtue of the cleaning advantage which it affords. At the rear of the base 11 there is provided an upstanding column or back stand generally designated by the reference numeral 13 which is secured in any

suitable manner to the base member. This back stand 13 is illustrated as somewhat in the form of a truncated pyramid, but obviously any other configuration may be employed.

For the purpose of providing a suitable support or shelf for a motor and various other elements of the multiple drink mixing machine, the upper end of the back stand or column 13 is provided with a horizontal supporting member 14 of generally U-shaped cross section which is secured in any suitable manner as by welding or the like to provide a suitable horizontal support. In order that this support or shelf may have sufficient strength, there is also provided a shelf reinforcement member 16, best shown in Fig. 6 of the drawings. This shelf reinforcement member is preferably provided at the ends thereof with L-shaped flanges 16a and 16b, whereby the shelf reinforcing member 16 is a sort of U-shaped member with the bight of the U being welded or otherwise secured to the horizontal support or shelf 14 and the short legs of the U being disposed in a vertical plane with lateral extensions from these legs being disposed in a horizontal plane. The legs and lateral extensions are designated by the reference numerals 16a and 16b.

In accordance with the present invention, there is provided a motor supporting spider generally designated by the reference numeral 18, which spider is formed as a sheet metal stamping rather than a casting such as has been heretofore employed. This motor supporting spider preferably comprises a one-piece stamping having a sort of dish-shaped central portion 18a which is disposed in an inverted position and from which the major portion of the bottom of the dish has been removed so as to define a large central opening 19. Integrally connected to the lowermost portion of the inverted dish-shaped central section 18a of the sheet metal spider 18 is an annular flange 18b, which flange has a configuration best shown in Fig. 2 of the drawings. It has a rectangular section 18c for permitting ready attachment to the shelf reinforcement 16 already described and a plurality of spaced projections 18d around the periphery thereof which determine the location of the individual mixing units. Between the different projections 18d the flange 18b has an arcuate configuration so that a sort of scalloped flange is provided, as is clearly shown in Fig. 2 of the drawings.

For the purpose of supporting the spider 18 in the position shown in the drawings, the rectangular projection 18c is suitably secured to the extensions 16a and 16b of the shelf reinforcement 16 as by fastening means 20. Preferably a pair of suitable soft rubber gaskets 21 are interposed between the ends of spider 18 and the portions 16a and 16b of the reinforcement 16 to prevent the vibrations from a suitable driving motor to be described hereinafter secured to the spider 18 from being transmitted to the supporting column 13 and the base 11. It will be apparent that the spider 18 as described thus far has a sort of cantilever support, but there is also described hereinafter an additional support for the spider 18.

With the present invention any type and manufacture of motor which can be accommodated in the space provided can be supported from the spider 18 in a very simple manner. To this end there is secured to the inside vertical wall of the dish-shaped section 18a of the spider a plurality of motor mounting lugs 22, best shown in Figs. 2, 3 and 4 of the drawings. These motor mounting lugs comprise a vertical portion 22a welded or otherwise secured to the spider 18 at any point on the periphery thereof, and a U-shaped portion 22b integrally secured to the vertically disposed portion 22a, which U-shaped portion includes an opening in one of the legs thereof to receive the conventional through bolts associated with electric motors for holding the motor in assembled condition. It will be apparent that these motor mounting lugs 22 can be positioned any place on the periphery of the spider 18 to accommodate the particular location of the lugs on any commercial motor. Moreover, the size of the U-shaped por-

tion can be varied as desired depending upon the diameter of the circle positioning the through bolts associated with the motor. In the drawings a motor 23 is indicated as having through or stator bolts 24 which extend through openings in the motor mounting lugs 22 to which bolts suitable nuts 25 are secured. Preferably and to insure very accurate positioning of the motor 23, the openings in the mounting lugs 22 are tapped and the stator bolts 24 threaded therein, thus eliminating the nuts 25. It will be apparent, therefore, that with such a stamped spider 18 any motor can be accommodated merely by modifying the lugs 22 which are manufactured as a separate operation, and great advantages are obtained as contrasted with the cast type spider usable only with a particular motor.

It will be apparent that with the motor 23 supported in the manner described the motor shaft generally designated by the reference numeral 26 will extend in a vertical direction and will actually protrude through the large opening 19 in the spider 18 with the motor disposed below this shaft 26, as viewed in Fig. 3 of the drawings.

To provide additional support and to completely enclose the motor and the lower portions of the mechanism drivingly related to the motor, there is provided what is commonly termed a top plate 28 and a skirt 29. The top plate 28 is of dish-shaped configuration having a circumferential extent somewhat commensurate with that of the base 11. As illustrated, the top plate 28 is of generally circular configuration while the base 11 comprises a portion of an octagonal configuration. Obviously, any suitable shapes of top plate and base may be employed. This top plate 28 of dish-shaped configuration with the dish-shaped construction in an upright position is provided with a central opening of sufficiently large diameter to accommodate the motor 23. The skirt 29, on the other hand, is disposed to surround the depending portion of the motor 23, and the upper edge of the skirt 29 engages the margin of the opening within the dish-shaped top plate 28 and is suitably secured thereto as by welding or the like. Thus, the skirt 29 and the top plate 28 are in effect a unitary structure which are so secured to the column 13 as to provide additional support for the spider 18. As illustrated, the back portion of the top plate 28 rests on top of the shelf reinforcement 16 and is suitably secured to the top of the column 13 as by screws 27 or the like. Moreover, the skirt 29 is provided with an inturned flange 29a, best shown in Figs. 2, 3 and 4 of the drawings, so as to be secured to the vertical column 13 as by fastening means 15. It will be apparent, therefore, that the skirt 29 in effect provides an effective shelf bracket for the top plate 28. To support the spider 18 from the top plate 28, a plurality of somewhat U-shaped spider supports 31 are secured as by welding or the like to the top plate 28 to engage with the spider 18 and support the same. Preferably suitable rubber washers, not shown, are interposed between the top plate 28 and the spider supports 31 to eliminate metal to metal contact and prevent the transmission of vibrations between the spider 18 and the top plate 28. Also, suitable fastening means 32 in the form of screws are provided which extend through the spider and engage tapped openings in the U-shaped supports 31, thereby further supporting the spider 18 from the top plate 28. The top plate 28 is provided with a plurality of openings 34 to accommodate individual mixing units to be described hereinafter as well as cooperating adjacent openings 35 for accommodating certain control means associated with each mixing unit.

For the purpose of transmitting rotary motion produced by the motor 23, the motor shaft 26 has affixed thereto a relatively large centrally disposed driving wheel indicated generally at 36 which is preferably formed of sheet metal and which may be similar or identical with the driving wheel disclosed in Prince et al. Patent 2,619,332, referred to above. This driving wheel 36 is secured to the shaft 26 in any suitable manner and is specifically illustrated as comprising a central hub

construction with a means for readily securing and releasing the same with respect to the shaft 26. The driving wheel 36 is provided on its periphery with a rubber tire or rim 37 suitably secured thereto. In order to provide a flow of cooling air over the motor 23, the lower side of the driving wheel 36 is preferably provided with a plurality of vanes 38 which upon rotation of the motor shaft 26 cause a stream of air to flow and cool the housing and windings of the motor 23 in a conventional manner.

As is fully disclosed in the above-mentioned Prince et al. Patent No. 2,619,332, there are provided a plurality of mixing heads or spindle assemblies generally indicated at 40 disposed in spaced relationship around the periphery of the motor 23. Actually each mixing head 40 is associated with a different one of the openings 34 in the top plate 28 and supported from a different one of the projections 18d of the spider 18. Each mixing unit comprises a mixing spindle 41 provided with conventional agitator units designated as 42.

For the purpose of supporting the respective spindle assemblies 40 around the periphery of the motor 23, the spider has secured thereto at each of the projections 18d one of a plurality of supporting members 44. Also secured to each of the spindle assemblies 40 are similar supporting members 45. These supporting members 44 and 45 are provided with somewhat circular end portions. The circular end portions 45a of the member 45 are clearly visible in Fig. 2 of the drawings and the ends of member 44 are substantially identical. These circular end portions are secured together with an interposed resilient rubber mounting member 46 thereby to provide a resilient support or hinge, whereby the respective spindle assemblies 40 are effectively pivoted about this hinge in a manner identical with that described in the above-mentioned Prince et al. patent, except that in the Prince et al. patent a resilient metal hinge is provided, whereas in the instant situation a hinge arrangement using interspersed rubber discs 46 is provided.

To enclose the spindle assemblies 40 and friction wheel 36, a suitable top cover 47 is provided secured to the top plate 28. As illustrated, the back stand 13 is provided with a recessed portion to receive an offset on the cover 47. Preferably also the cover is secured to the back stand 13 by fastening means such as screws, not shown.

For the purpose of further relating the spindle assemblies 40 to the spider 18 the upper end of each spindle assembly 40 is provided with a clevis like extension 48 which is connected as by means of a pivot pin 49 with a toggle comprising links 50 and 51, the knee of the toggle being defined by the pivot pin 52. The other end of the toggle comprising links 50 and 51 is connected by a pivot pin 53 with an I-bolt 54. This I-bolt is effectively a lug which extends through a link rest 55 and through a cooperating opening in the spider 18 so that it may be riveted as indicated at 56. With this arrangement it will be apparent that by movement of the pivot pin 52 which defines the knee of the toggle the spindle assembly 40 may be caused to describe a slight pivotal movement about the hinge arrangement by which the spindle assemblies 40 are secured to the spider 18. Although only a single spindle assembly 40 and its supporting means is described in detail, it will be understood that as many such spindle assemblies as desired may be mounted around the periphery of the motor 23. As illustrated in Fig. 2 of the drawings, five such spindle assemblies 40 are provided and are disposed with their lower ends extending into the openings 34 and the spindle shafts 41 depending downwardly in spaced relationship around the skirt 29. Preferably the skirt 29 and the top plate 28 are also formed of stainless steel like the base 11 for providing a nice appearing finish and a readily cleanable surface so that all sanitary requirements are met.

It will be appreciated and as fully disclosed in Prince et al. Patent No. 2,619,332 that the spindle assemblies 40 comprise a housing for supporting suitable bearings within which the mixing spindles 41 are journaled for rotation. Each of these mixing spindles has secured thereto a suitable friction wheel 60 which is preferably identical with that disclosed in Patent 2,619,332 and also disposed adjacent the bearings so that no undue bearing wear results. Each friction wheel 60 is positioned in a manner to engage the friction drive wheel 36. As illustrated in Fig. 3 of the drawings, when the toggle is in the normal straight position the friction drive wheels 60 are spaced from the friction rim 37 of the drive wheel 36, but, when the knee or pivot pin 52 of the toggle joint is displaced upwardly in a position off the center toggle position as shown in Fig. 4 of the drawings the friction wheel 60 whose toggle joint is disturbed in the manner described is moved into driving engagement with the friction wheel 36. It will be apparent that the friction wheel 36 will drive as many or as few of the spindle friction wheels 60 as are moved into driving engagement therewith. In other words, all of the mixing spindles 40 can be simultaneously driven or as few as one may be driven by the motor 23.

For the purpose of causing movement of the mixing spindle friction wheel 60 into engagement with the friction drive wheel 36 in response to initiating a mixing operation, there is provided for each spindle assembly 40 a plunger 62 mounted for vertical movement within the associated opening 35. Each of the plungers 62 has a lower slot 62a designed to receive the rim of a cup or the rim of a mixing vessel as disclosed in Fig. 4 of the drawings. The particular mixing cup employed is immaterial as far as the present invention is concerned. Actually, this mixing cup may comprise a paper cup in which the mix is to be served, a separate mixing vessel of metal or other suitable material as is commonly used in such applications, or it may comprise a paper mixing cup such as indicated at 63 with a metal sleeve 64 which may be temporarily attached thereto in a manner fully disclosed in Fredenhagen et al. Patent No. 2,628,082. The cup 63 and the sleeve 64 may together be considered the mixing vessel and the portion 62a of the plunger 62 is adapted to receive as is clearly shown in Fig. 4 of the drawings, the rim of the mixing vessel which rim is designated by the reference numeral 64a. As illustrated in the drawings the plunger 62 is provided with a portion 62b of reduced cross section so as to define a shoulder 65 thereon. Resting on the shoulder 65 in accordance with the present invention is a lifter 66 which includes the necessary opening to permit the reduced portion 62b of the plunger 62 to pass therethrough. The lifter 66 has a pair of laterally extending fingers with depending ends 66a which engage with a flattened surface 62e of the plunger 62 so that the lifter 66 remains in a predetermined position. The lifter 66 is held in position by means of a coil spring 70 concentric with the reduced section 62b of the plunger 62 and the upper end of the plunger 62 is provided with an elongated slot 71 which is connected to the knee of the toggle comprising the links 50 and 51, or in other words, is connected to the pivot pin 52. The elongated slot 71 provides a lost motion connection so that a predetermined upward movement of the plunger 70 can be occasioned before the knee of the toggle link is moved from the position shown in Fig. 3 to the position shown in Fig. 4, and also for the purpose of accommodating slight variations in the overall length of the mixing vessels. It also provides sufficient movement to insure actuation of a switch described hereinafter.

In order to make sure that the rim 64a of the mixing vessel does not move between the skirt 29 and the particular plunger 62 being actuated, the skirt 29 in accordance with the present invention is provided with a plurality of indentations 75, one adjacent each plunger 62 and the

plunger portion 62a is so defined that a portion thereof is disposed within the indentation 75 thereby making sure that it is impossible to push the edge of the mixing vessel between the plungers 62 and the skirt 29.

To support the mixing vessel in the mixing position shown in Fig. 4 of the drawings, a plurality of cup rests generally designated at 76 are provided. These cup rests are best shown in Figs. 4 and 5 of the drawings. As illustrated, each cup rest comprises a securing flange 76a having suitably secured thereto a somewhat U-shaped cup support 76b. This cup support 76b has one leg secured to the flange 76a with the bight of the U projecting from the securing flange 76a and the other leg of the U defining a sort of angularly disposed lip to prevent the cup from slipping off the cup rest 76 when once positioned thereon as indicated in Fig. 4 of the drawings.

Suitable means 77 are provided to secure the cup rests 76 to the skirt 29. It will be apparent that the operator in associating a mixing vessel with a particular mixing spindle 40 merely moves the mixing vessel into a position so that the mixing spindle 41 moves into the vessel and the rim 64a of the mixing vessel engages the plunger 62 as illustrated in Fig. 4 of the drawings. The plunger is then moved upwardly by engagement with the mixing vessel until the lower end of the mixing vessel rests on the cup rest 76. Due to the indentation 75 it is impossible to slip the mixing vessel between the skirt 29 and the plunger 62.

For the purpose of controlling the energization of the motor, a suitable switch 79 is provided which is indicated as being supported by the portion 18c of the spider 18 in any suitable manner. It will be appreciated that a suitable power cord is connected to the motor 23 through the switch 79 so that unless the switch 79 is closed power cannot be supplied to the motor.

In order automatically to energize the motor whenever a mixing vessel is associated with any spindle assembly such as 40, there is provided in accordance with the present invention a mechanism for actuating the switch 79 in response to the upward movement of any one or all of the plungers 62. To this end there is provided a lever 80 in the form of a ring which is not quite a complete circle and which at the discontinuous portion thereof is provided with a plurality of extensions 80a and 80b which is suitably pivoted as indicated at 81 to a supporting member 82 secured to the spider 18 in any suitable manner. The supporting member 82 preferably also suitably supports the switch 79. Also secured to the lever 80 is a switch actuating member 83 adapted to engage the switch 79 in any suitable manner so that upon slight pivotal movement of the lever 80 the switch 79 is actuated. The lever 80 is mounted so that the circular portion thereof loosely encircles the dish-shaped central portion 18a of the spider 18 and is disposed immediately above the individual lifters 66 associated with each plunger 62. It will be apparent that when any plunger 62 is moved upwardly the cooperating lifter 66 likewise is moved upwardly to engage the lever 80 and hence close the switch 79. A suitable spring 84 illustrated as a tension spring is associated with the switch actuator 83 to bias the lever 80 in a direction to maintain the switch 79 closed. Hence whenever all of the plungers 62 are in the position shown in Fig. 3 of the drawings, the switch 79 will be open. However, the raising of any plunger 62 will automatically close the switch 79. With this arrangement it will be apparent that the operator can have mixing vessel in each hand and need never first turn on the motor 23 before the mixing operations can occur. In this way the operator is free to position the mixing vessels on their supports and move them about to insure the proper mixing action without having to set one down to turn on a switch or the like, and when none of the mixing assemblies 40 is required to perform a mixing operation, the switch 79 is automatically opened and the motor 23 deenergized.

In view of the detailed description included above, the operation of the multisindle drink mixing machine of the present invention will readily be understood by those skilled in the art. It will, moreover, be appreciated that there has been provided an inexpensive motor supporting arrangement which can readily accommodate standard motors produced by various manufacturers with the same supporting means. Furthermore, there has been provided an improved control arrangement.

10 While a particular embodiment of the invention has been shown, it will be understood, of course, that the invention is not limited thereto, since many modifications may be made, and it is, therefore, contemplated by the appended claims to cover any such modifications as fall within the true spirit and scope of the invention.

What is claimed as new and desired to be secured by Letters Patent of the United States is:

1. A multiple drink mixing machine comprising a support, a spider mounted on said support and including a 20 circular center portion, a motor mounted on said spider, a master driving wheel driven by said motor, a plurality of mixing spindles mounted on said spider around said circular center portion, a plurality of spindle driving means, one associated with each of said spindles for 25 selectively driving any one or more of said spindles from said master driving wheel, an energization circuit for said motor including a control switch, a switch actuating member in the form of an open ring pivotally mounted to said spider at the open end thereof and including means for operating said switch, said open ring including a circular section extending around said center portion, container actuated plungers one for each spindle for rendering the associated spindle, driving means effective to drive said associated spindle from said master driving wheel, said 30 container actuated plungers being spaced around a circle having a diameter of the order of the diameter of said circular section, and means on each of said container actuated plungers for engaging a different part of said circular section for operating said switch actuating member to close said switch in response to operation of said container actuated plungers whereby said motor is energized whenever said master driving wheel is in driving engagement with any one of said spindle driving means.

2. In a multiple drink mixing machine, the combination of a support, a motor mounted on said support, a master driving wheel driven by said motor, a plurality of mixing spindles mounted on said support each including a friction wheel, said mixing spindles being arranged in a circle around said master driving wheel, a plurality 40 of spindle driving means, one associated with each of said spindles for selectively moving one or more of said friction wheels into driving engagement with said master driving wheel, an energization circuit for said motor including a control switch, a switch actuating member including a circular portion extending around a substantial portion of said circle for operating said switch, container actuated means one for each spindle for rendering the associated spindle driving means effective to drive said associated spindle from said master driving wheel, 45 said container actuated means comprising a non-rotatable rod having an inwardly extending portion which is adapted to engage said circular portion of said switch actuating member to close said switch when said rod is actuated by a container to selectively move its respective friction wheel into driving engagement with said master driving wheel whereby said motor is energized whenever said master driving wheel is in driving engagement with any one of said spindle driving means.

3. In a multiple drink mixing machine the combination of a support, a motor mounted on said support, a master driving wheel driven by said motor, a plurality of mixing spindles mounted on said support, a plurality of spindle driving means one associated with each of said spindles for selectively driving any one or more of said 50 spindles from said master driving wheel, an energization

circuit for said motor including a control switch, a pivoted switch actuating ring for operating said switch, vertically movable container actuated means one for each spindle for pivoting said ring and for simultaneously rendering the associated spindle driving means effective to drive said associated spindle from said master driving wheel, a depending skirt provided around said motor between said motor and said mixing spindles, said skirt having a plurality of recesses defined by deformations in said skirt one adjacent each spindle and each adapted to house only a portion of the respective container actuated plunger, the operating portions of said actuating plungers being disposed without said recesses, whereby when a container is moved into mixing position operation of said container actuated means is assured.

4. In a multiple drink mixing machine, the combination of a plurality of mixing spindles, an electric motor for selectively driving said spindles, said motor having conventional stator bolts for holding said motor in assembled condition, the combination of a support for said electric motor comprising a stamped spider including a cylindrical center portion and a flange extending from said center portion, motor supporting lugs each including a straight portion secured to the inside of said cylindrical center portion and a U-shaped portion, each U-shaped portion including an opening in one leg thereof for receiving one end of one of said stator bolts of said motor thereby to support said motor from said spider, said lugs being positioned on said circular portion in dependence upon the relative positions of said stator bolts and said openings being positioned in accordance with the diameter of a circle upon which said stator bolts are located whereby a wide variety of motors may readily be supported from said spider.

5. A multiple drink mixing machine comprising a plu- 30

rality of mixing spindles, an electric motor for selectively driving said spindles, said motor having conventional stator bolts for holding said motor in assembled condition, the combination of a support for said electric motor comprising a stamped spider including a cylindrical center portion and a flange extending from said center portion, means for supporting said mixing spindles from said flange in spaced relationship around said center portion, motor supporting lugs each including a straight portion secured to the inside of said cylindrical center portion and a U-shaped portion, said U-shaped portions including an opening in one leg thereof for receiving one end of one of said stator bolts of said motor thereby to support said motor from said spider, said lugs being positioned on said circular portion in dependence upon the relative positions of said stator bolts and said openings being positioned in accordance with the diameter of a circle upon which said stator bolts are located whereby a wide variety of motors may readily be supported from said spider.

6. The drink mixing machine of claim 5 comprising an energization circuit for said motor including a control switch, and a circular switch actuating member pivotally supported on said spider and encircling said cylindrical center portion.
